STRAP STRETCHING AND FASTENING TOOL

Filed Oct. 15, 1927

Inventor:

Joseph Bayer

UNITED STATES PATENT OFFICE

JOSEF BAYER, OF BARMEN, GERMANY

STRAP STRETCHING AND FASTENING TOOL

Application filed October 15, 1927, Serial No. 226,476, and in Germany April 20, 1927.

This invention relates to a bale-tie fastener of the kind described in the specification of Patent No. 1,517,903 wherein the bale band is strained by means of a radially displaceable serrated wheel and wherein the sealing of the band ends is effected by means of a crimping tool, the latter and a lever which operates the straining wheel by means of a pawl and ratchet mechanism, being pivoted to a supporting frame.

The object of the invention is to produce a device of very simple construction, and the invention consists in providing the supporting frame with a rearward extension serving as a handle, the straining lever being arranged under said handle and the sealing tool in front of it, the lever and tool being operable in the vertical plane of the extension.

20 The invention is illustrated in the accompanying drawing which represents a side view showing the fastener in operation.

The bale-tie fastener comprises a supporting frame *b* provided with a base plate *k*, 25 with a foot *n*, and with a rearward extension *s* serving as a handle. The foot *n*, has a groove *n*¹ whereby the device is positioned on the steel or like band to be strained and fastened. The overlapping band ends are 30 carried over the base plate *k* which is provided with a serrated steel anvil *l*. Over the latter a straining wheel is arranged which, as described in the specification of Patent No. 1,517,903, is adapted to be lowered for 35 pressing the band ends to the anvil and to be rotated for sliding the upper end over the lower one which is retained by the anvil. The lever for rotating the straining wheel is according to the invention arranged under the handle *s* and pivoted at *v* to the frame *b*. A pawl pivoted at *f* to the lever co-operates with a ratchet wheel connected to the straining wheel for rotating the latter.

The tie is sealed by crimping the overlapping band ends. This is effected by means 45 of a crimping tool comprising a pair of jaws *q* which are pivotally mounted between two plates *t* and *t*¹ and operated by means of a pair of shear levers *r*. The plate *t*¹ is 50 provided with lugs *u*¹ whereby the crimping

tool is pivoted at *u*² to the upper front portion of the frame *b*. The crimping is effected in front of the forward projection *k*¹ of the base plate, the crimping tool being turned into a vertical position for use as 55 shown in the drawing.

I claim:

A bale-tie fastener of the character described, comprising a frame having an upward and rearward extension forming a 60 handle, a straining lever arranged under said extension and pivoted to the frame, and a crimping and sealing tool pivoted to said frame in front of the extension, said lever and sealing tool being movable in the vertical plane of the extension.

JOSEF BAYER.
